UNITED STATES PATENT OFFICE

HENRY E. IRWIN, OF MONTCLAIR, NEW JERSEY, ASSIGNOR TO R. R. HEYWOOD COMPANY, INC., A CORPORATION OF NEW YORK

DISPLAY DEVICE

Application filed September 19, 1928. Serial No. 306,878.

My invention relates to a device by means of which samples of greeting cards and of materials to be used in the linings of envelopes distributed therewith, may be displayed together in such relation as to indicate the appearance of the linings in the finished envelopes and to permit comparison thereof with the color schemes of the particular cards being displayed therewith, 10 without necessitating display of the finished envelopes.

Manufacturers of greeting cards, prior to the time that tissue-lined envelopes were used, in displaying and selling the cards to the distributing trade, customarily sampled the card itself without any envelope being shown, but as soon as envelopes were used with linings it was then necessary to display the envelope showing the lining, not only for 20 the purpose of indicating the quality of the lining itself, but also to indicate how the lining harmonizes with the color scheme of the card.

Greeting cards are reproduced from sketches, some of which are in full color, and some just in the black and white, in which case the color schemes are made after the cards are printed or stamped. Whichever way is employed, it is not practicable to 30 match the lining to the design of the card until the card is completely finished as to the color of the stock and the color of the design. Therefore, in getting out a new line of greeting cards, it has been the custom for the manufacturer either to buy for each design made a number of envelopes with different linings, 35 in order to be able, when the cards were sampled, to get one of the linings to harmonize with the color scheme of the card, or else to buy a number of plain envelopes, tissue lined style, and to select the linings and line the envelopes by hand for each design.

When it is considered that a normal line of cards comprises several hundred numbers of 45 thirty or forty different color stocks, and that these may take twelve or fifteen different sizes and shapes, it will be appreciated that the former method was expensive because of the surplus of sample envelopes left over of 50 the designs of linings which were not selected,

while the latter method meant not only a loss of time in getting the sample cards out, but also considerable expense for labor in lining the envelopes by hand.

The present invention has for an object a saving in expense as compared with the completely manufactured envelope or the hand-lined envelope for sampling, and also a saving of time in mounting the display cards, which in turn makes it possible to advance the date of the showing of the new line.

Other objects of the invention will appear from the following detailed description and the accompanying drawings, in which:

Fig. 1 is a front elevation of my improved display device, comprising a supporting sheet member and a sample greeting card carried thereby; and

Fig. 2 is a horizontal section on the line 2—2 of Fig. 1.

Referring to the drawing, the numeral 1 indicates generally a supporting sheet member, which may be of cardboard or any relatively stiff, sheet material.

Lines 2, 3, 4, 5, 6 and 7 are shown on the sheet member 1 to simulate the outline and the lines of intersection of the folds of the back of an envelope, and in the space defined by the lines 2, 4 and 5, and conforming substantially to the shape and size of the opening normally covered by the flap of an envelope, is an opening 8. A sheet or strip 9 of lining material of a color and appearance adapted to harmonize with the color scheme of the card being displayed is shown as secured or affixed to the back of the card in such position as to cover the opening 8. The greeting card 10 is mounted on the front of the card in such position as to be adjacent the opening 8 in order that the color of the lining may be easily compared with the color scheme of the card.

A simple and convenient way of securing the card and the lining material to the sheet 95 1 is by means of a suitable adhesive. It will be understood, of course, that any other method of either permanently or temporarily attaching the lining material and the card to the support may be employed.

Various changes in the details of the con-

struction may be made without departing from the invention which is not to be deemed as limited other than as indicated in the appended claim.

5. What I claim is:

In a device of the character described, a sheet having the outlines of an envelope and the lines of intersection of the folds thereof depicted thereon and provided with an opening therethrough, the edges of which are determined by that portion of said outlines and the lines of intersection that define the flap, and a strip of lining material affixed to the back of said sheet to cover said opening and to display the lining therethrough.

In testimony whereof, I have signed my name to this specification.

HENRY E. IRWIN.
